UNITED STATES PATENT OFFICE.

SILAS C. SALISBURY, OF NEW YORK, ASSIGNOR TO LEVI P. ROSE, OF YONKERS, N. Y.

APPARATUS FOR MANUFACTURING ILLUMINATING-GAS.

SPECIFICATION forming part of Letters Patent No. 317,581, dated May 12, 1885.

Application filed June 6, 1884. (No model.)

To all whom it may concern:

Be it known that I, SILAS C. SALISBURY, of the city, county, and State of New York, have invented new and useful Improvements in Apparatus for Manufacturing Illuminating-Gas, of which the following is a full and accurate description.

This invention relates to the method and apparatus for making gas for which Letters Patent were granted to me on the 24th day of June, 1884; and it consists, first, in an iron retort adapted to decompose steam, protected by a jacket of clay or other refractory material, as I have found that the iron retorts described in my patents above referred to are subjected to a heat much more intense than is required, and they are therefore rendered less durable without increased efficiency; second, in the perforated diaphragms whereby the retort is separated into chambers, constructed of iron plates cast with projecting hollow hubs or tubes, said plates being joined by rods, so that they are mutually supporting and may be easily removed or replaced, whereby the retort is relieved from the greater weight of the thick perforated tiles without decreasing the area of the friction-surfaces in the tubes to which the gases are subjected in passing; third, in providing with each mixing and fixing retort an extra hydrogen-pipe, whereby the quantity of hydrogen delivered to the hydrocarbon mixture may be varied without changing the adjustments at the mixing-injector, so that the richness in carbon may be regulated and varied at pleasure without any change in the action of the injector.

Exposure to the direct action of the flames causes the naked iron pipes to be heated greatly above the requisite degree, which is about 40 cherry red, and the destruction of the metal is therefore increased without any corresponding increase in efficiency. To obviate this unnecessary destruction and to render the pipes more durable and more uniform in their action by 45 rendering their temperature more uniform, I place my decomposing and mixing pipes within a clay jacket, and I find it convenient for this purpose to employ an ordinary clay retort. Ordinary perforated tiles, when continuously subjected to a high heat, become friable and 50 crack and crumble, and I have therefore found

that the perforations will sometimes become obstructed, and the failure in any way of a single perforated tile partition will disable the whole retort. The great weight of the tile partition will also sometimes cause the heated retort to sag or crack at the bottom. To obviate these difficulties I now make the perforated partitions whereby I divide the fixing-retort into separate chambers of these cast-iron plates, having hollow hubs or tubes about four inches in length and three-fourths of an inch internal diameter cast integral; or, if preferred, short lengths of suitable pipes may be set in the mold and the molten iron cast 60 around them. These plates afford the necessary separation into chambers with a desirable length of friction-surface in the tubes, through which the hot gases rush and rub with less weight and no tendency to crumble 65 or break down.

My pipes, being all inclosed, are protected from any chilling by contact with the outside air. The heat to which they are subjected may be controlled and graduated, so that the 75 gases are subjected to an increasing heat from the time they enter the mixing-pipe until they leave the fixing-retort.

The maximum efficiency of any injector is attained by an adjustment of volume and velocity of the jet to a definite volume of induced or injected fluid. This definite relation need not be stated here, because it varies with the fluids employed, and because it is not necessary to a statement that when it has been attained any change in the volumes or velocities will be at the expense of efficiency. Therefore, to increase or diminish the relative proportions of hydrogen and hydrocarbon passing from the mixing-injector will disturb the 90 action of the injector and cause a loss in efficiency. I therefore adjust the injector to move the maximum volume of hydrocarbon and introduce an extra hydrogen-pipe, whereby the supply of hydrogen to reduce the richness or 95 standard of the resulting gas may be regulated independently of the mixing-injector.

Figure 1 is a front view of a bench of five retorts with all of my attachments placed ready for use. Fig. 2 is a longitudinal section through retorts A B. Fig. 3 is a longitudinal section of the mixing-injector.

Retort A is used expressly for producing hydrogen gas from superheated steam. Retorts B C D E are used for mixing and fixing the gas. A double superheating steam-pipe 5 and an eight-inch or ten-inch diameter iron retort filled with small pipes or iron borings, &c., are placed in retort A. The steam-pipe 1 from the boiler is connected with the inner superheating-pipe, 2, and discharges the first 10 superheated steam against the closed inner end of the outer pipe, 3. It returns to front between the two red-hot surfaces of the pipes 2 and 3, and then passes from the front end of the outer pipe, 3, into another superheating-pipe, 4, leading into the front end of the iron retort 5 and back to within two inches of rear end thereof, where the finished, dry, red-hot superheated steam is discharged. It then returns to the front end of said retort 5 through 15 the red-hot iron scraps or pieces of pipe, and during its passage it becomes decomposed, the oxygen being absorbed by the iron, and the liberated gas from the decomposed superheated steam passes into a pipe, 6, leading to the main pipe 7, and from this main distributing-pipe branch pipes 8 are attached, leading to the inner shell of each of the mixing-injectors 9, each of which is attached to a hydrocarbon-pipe, 11, whereby the hot hydrocarbon vapor or liquid spray is blown into the hydrocarbon heating and mixing pipes 10, and thence to the rear end of each of the clay retorts B C D E.

Number 11 are the oil-pipes, which are attached to the outer shell of each one of the mixing heating-injectors where the hot oils are delivered in regulated quantities, the hydrogen being delivered red-hot into the inner shell, which becomes red-hot and heats the oil or naphtha to a vapor, which is by force discharged into the hydrocarbon heating and mixing pipe leading from the front to the rear end of each of the retorts B C D E, where the red-hot hydrocarbon vapor is discharged, as 35 more fully shown in Fig. 2, which shows a vertical longitudinal section of a fixing-retort and a similar section of the decomposing or hydrogen retort with the iron retort 5 and double superheating-pipes 2 and 3, with all 40 their connection, as fitted together inside the clay retort, forming a continuous connection from the steam-pipes to discharge of hydrogen or decomposed steam to pipe leading to the distributing-pipe.

The upper section in Fig. 2 shows the interior view of retorts B C D E of the bench shown in Fig. 1, with the partitions 12 having hollow hubs or tubes four inches long and three-fourths of an inch interior diameter cast 50 into them. These plates form the separate apartments or mixing-chambers G, and are connected together by iron braces 14. The hydrocarbon heating and mixing pipe 10 is connected with the mixing-injector at the front end and discharges the hot vapors therefrom into the rear end of the last chamber. As this hot vapor is discharged it expands, 55

and thence has to pass through the red-hot pipes 13, where it is subjected to friction and further heating by the red-hot surfaces and 60 the remaining free oxygen is absorbed, and so on through each section and mixing-chamber to the uptake stand-pipes 20. During this described process a most thorough union of all the gases takes place, and they remain 65 permanently fixed.

An extra hydrogen-pipe, 15, leads from the distributing hydrogen-pipe 7 to each one of the retorts B C D E, from front to rear end, alongside of the heating and mixing hydrocarbon-pipes 10. This hydrogen-pipe 15 discharges red-hot hydrogen gas in and among the red-hot hydrocarbon vapors, the object of which is to reduce the rich quality of such hydrocarbon vapor—say from a forty-candle power to a twenty or twenty-five candle power—ere it becomes a fixed gas by its passage through the red-hot pipes and mixing-chambers, as this is found to be the safest and best mode of reducing to a uniform standard of 80 twenty-five-candle gas when all hydrocarbon liquids are used for manufacturing gas by this continued process. Fig. 3 shows the mixing and heating injector as fitted with the oil and hydrogen pipes, and also shows the discharge 85 into the hydrocarbon-vapor pipe 10.

In Fig. 1 is shown an injector, 19, with its oil and hydrogen pipes connected to and discharging its red-hot vapor-gas into the furnace. It is discharged among red-hot bricks laid on 90 grates for the purpose of heating the furnace and retorts contained therein. The air that may become necessary for perfected combustion enters underneath the grate-surfaces and passes up through the spaces of red-hot brick, 95 and becomes highly heated ere it comes in contact with the blaze and gas-vapors, and perfects combustion and utilizes all of the carbon.

In Fig. 1 retorts A and C are shown with their caps removed. The several controlling-valves are indicated by 16.

Having described my invention, I claim as new—

1. A superheating steam-pipe taking steam from the boiler, and placed within an outer superheating steam-pipe, and arranged in such a manner that the steam from the boiler shall first pass through the inner superheating-pipe and be discharged at the rear end of the outer pipe, through which it returns to the front, 115 passing over the red-hot surface of the inner pipe and outer pipes, and an iron retort charged with small iron pipes or iron scraps for decomposing superheated steam, connected with said superheating-pipes, and all inclosed 120 within and combined with a clay jacket, whereby the iron pipes and retorts are protected from contact with the flames of the furnace-fire, substantially as and for the purpose set forth.

2. The pipe 2, arranged to take steam from the injector, the inclosing-pipe 3, stopped at its rear end, within which pipe 2 is placed, as shown, and the pipe 4, connected at one end 130

with said pipe 3, and at the other end discharging into the retort 5, which is packed with scraps of iron, and the whole inclosed with a clay gas-retort, as and for the purpose set forth.

5 3. The cast-iron partition-plates 12, provided with the hollow hubs or tubes 13, substantially as described, placed within and combined with the clay retort, to divide the same into separate mixing and fixing chambers without 10 overloading said retort, as set forth.

4. A gas-retort provided with cast-iron partition-plates 12, each of said plates having the hollow hubs or tubes 13, said plates being attached together and supported by stay-rods 15 14, and the mixing-pipe 10, whereby hydrocarbon vapors and the gases of decomposed steam are conveyed to and discharged at the rear end of said retort, as and for the purpose set forth.

20 5. A steam superheating and decomposing retort inclosed within a jacket of refractory clay, combined with a fixing and perfecting gas-retort having the several cast-iron plates 12, provided with the iron pipes 13, placed in- 25 side each gas-retort, constituting mixing and

fixing chambers G, combined with a heating hydrocarbon-vapor pipe, 10, running from front to rear end of retort, for the purpose of reheating and mixing and fixing the hydrocarbon vapor, whereby the vapors at all 30 stages of the process are protected from chilling and may be subjected to continually increasing heat, thus perfecting a permanent fixed gas, as herein set forth and described.

6. A mixing and fixing retort and a mixing 35 and forcing injector to force hydrocarbon into said retort by means of the hot gases from decomposed steam, combined with an extra hydrogen-pipe adapted to discharge hydrogen into said retort independently of said injector, 40 whereby the injector may be adjusted for maximum efficiency and the richness or standard of the resultant gases may be regulated and controlled by the volume of hydrogen introduced through said extra pipe.
